QUICK-ACTING BENCH VISE

Joseph A. Follmer and Joseph Follmer,
Denver, Colo.

Application December 30, 1949, Serial No. 136,048

4 Claims. (Cl. 144—307)

1

This invention relates to woodworkers' quick acting bench vises and more particularly to improvements in vises of the general type disclosed in the patent to Joseph A. Follmer et al. No. 2,437,351, granted March 9, 1948.

One of the objects of the present invention is to provide a vise of the foregoing type in which the movable jaw of the vise may be positioned against the work piece and tightened thereagainst with only a fraction of a turn of the vise screw.

Another object is to provide a vise in which the slideable jaw is one-way-acting; that is, freely slideable upon rotation of the vise screw in one direction and engageable with the work piece upon rotation of the screw in the other direction.

Another object is to provide the vise with miter edges for engaging the work for quickly positioning the same at a 45° angle to the horizontal.

Another object is to provide the vise with improved means for securing it to a workbench.

A further object is to provide a vise with an improved bench stop.

Still further objects, advantages and salient features will become more apparent from a consideration of the description to follow, the appended claims, and the accompanying drawing, in which:

Figure 1 is a top plan of the vise;

Figure 2 is a side elevation;

Figure 3 is a section taken on line 3—3, Figure 2;

Figure 4 is a section taken on line 4—4, Figure 1;

Figure 5 is an enlarged section taken on line 5—5, Figure 2;

Figure 6 is a section taken on line 6—6, Figure 5;

Figure 7 is an enlarged section, similar to Figure 5, showing certain parts in another operative position;

Figure 8 is a section similar to Figure 6 showing certain parts in another operative position;

Figure 9 is a side elevation of a bench or vise stop employed with any of the figures; and

Figure 10 is a section similar to Figures 5 and 7, showing an alternative form of the invention, portions being broken away.

Referring in detail to the drawing, and particularly Figures 1 to 9, the vise comprises, in general, an elongated frame or body 10 having a jaw 11 slideably mounted thereon, actuated by a screw 12 which threadedly engages a plurality of nuts 13, 13a releasably engaging the body.

Body 10 is constructed as an elongated member

having a laterally projecting flange 14 at one end thereof and a similar, but somewhat longer, flange 15 at its other end. One face of the member is provided with grooves 16, 16a, as best shown in Figure 3, which form rectilinear guide means for the movable jaw. At the end adjacent flange 15 a lug 17 projects from one side of the member 10 which is provided with an unthreaded circular bore for slideably and rotatably receiving the vise screw therein. The upper edge of member 10 is provided with a 45° bevel 18 and a similar bevel 19, in the same plane thereof, is provided on the upper edge of the guide means, for a purpose to be hereinafter described.

15 In securing the vise body to a conventional bench 28 a bar of wood 21, having rectangular bench stop openings 22 therein, is secured to the edge of the bench and a recess 23 is cut in the bench top to receive the vise body in a manner such that the outside face of the bar and the outside face of the slideable jaw are in the same plane. A slot 24 is cut to receive flange 14, and flange 15 abuts one end of the bench. Screws 25 extend through body 10 and into the bench and screws 26 similarly extend through flange 15 into the bench. It will be observed that flange 14, disposed in slot 24, precludes any tendency for the vise body to move longitudinally of the bench when the vise is tightened and hence no substantial shear is taken by screws 25, these, and screws 26, serving to resist any transverse forces acting between the vise body and bench.

20 The slideable jaw 11 is provided with guide means 27, 27a which mate with and slide in grooves 16, 16a respectively, of the vise body member. A boss 28 is disposed on the jaw which is provided with a circular blind hole 29 having an abutment surface 30 at its inner end.

The vise screw 12 is provided with a groove 31 near one end thereof into which the end of a screw 32 projects to prevent separation of the jaw and screw. It will be observed that the entire end of the screw abuts surface 30, thus providing relatively large abutment surfaces which reduce any tendency of the end of the screw to swage as a result of use or excessive pressures on the abutment surfaces. The other end of the screw has affixed thereto a T fitting 33 which slideably receives a vise handle 34.

25 The quick acting jaw actuating means, which constitutes an important feature of the invention, comprises a plurality of spaced notches 35 disposed in the face of body member 10 forming abutment means 35a, therebetween, a flat, surface 36 thereon, and a pair of threaded nuts 13,

13a, each having an upper notch engaging ear 37 and a lower flat surface engaging ear 38 thereon. The threaded engagement of the nuts on the screw provides sufficient friction such that rotation of the screw will carry the nuts with them until resisted from further movement by abutment of lower ears 38 with flat surface 36, or by abutment of an upper ear 37 within a notch or against the body member between notches. In the embodiment shown in Figures 1 to 9 the pitch of the notches is twice the lead of the screw, the latter being double threaded.

Assuming that the vise is wide open with ears 38 in engagement with surface 36, a work piece may be inserted between jaw 11 and the end of bar 21, which forms a fixed jaw, and the jaw 11 slid into engagement therewith by application of force to the outer end of the screw. When the movable jaw abuts the work piece the handle is then rotated, which rotates the nuts to a position adjacent the notches. If one of ears 37 happens to align with a slot, as shown in Figures 5 and 6, for example, it will enter it and upon further rotation of the screw such ear prevents movement of the nut and the work piece may then be tightened between the jaws. If neither of ears 37 happens to be aligned with a slot, a partial rotation of the screw will move the nuts until one of the ears is rotated into a slot. In the construction shown in Figures 1 to 9 the pitch of the slots is twice the lead of the screw, and the slots and ears are so proportioned that one of the latter will enter one of the former in not to exceed one revolution of the screw after the movable jaw has engaged the work piece.

In Figure 10 is shown a manner in which the vise may be rendered still more quick acting. In this construction one or more plates 39 having ears 37, 38 thereon are interposed between the nuts, these being either threaded or unthreaded and mounted on the screw. With this construction an ear 37 will usually be in a position to enter a slot, but in any event, a lesser amount of rotation of the screw will be required to align one of the ears with a slot. Two plates have been illustrated, but it will be apparent that any number may be employed and that as the number is increased the sensitivity of the vise will be increased. In other words, the larger the number of ears 37 present, the lesser will be the maximum amount of screw rotation to effect locking of the nut mechanism to body 10.

In the construction just described, the ears may be omitted from nut 13, if desired, nut 13a may be unthreaded, but secured to nut 13 by any suitable bridging or spacing means, and the locking of the nut mechanism effected by engagement of one of the ears on plates 39 with abutments 35a, rather than by such ears on the nuts.

The slideable jaw is provided with a square or rectangular hole 49 therethrough, similar to openings 22, for receiving a bench stop 41 which comprises a square or rectangular bar having a lower tapered end to which is secured a flat spring 42 by means of a rivet 43, or the like. The spring engages one wall of the hole and retains the stop at a desired position of adjustment above the movable vise jaw. When not in use, it is depressed into the movable jaw so that its top surface is flush with the top of the jaw.

The novel nut mechanism is an important feature of the invention, and while a double

threaded screw has been mentioned, it is apparent that the screw may be made with a single thread or any number of multiple threads. The nut mechanism may also be modified to render it as sensitive as desired so that only a small angle of rotation of the screw is necessary to engage a locking ear 37 with an abutment 35a, this, by merely increasing the number of ears available to be rotated into a slot. It will be noted that the upper and lower ears of the plates 39 are disposed so that they substantially balance the plates on the screw and hence only a very slight amount of friction, on the screw, is required to rotate one of them into a slot. They may be threaded, if desired, but unthreaded plates have sufficient friction on the outside of screw threads to effect the requisite rotation.

In our prior identified patent the slideable jaw is double acting; that is, it may be made to move under control of the screw in either direction of rotation. While a position of release is possible in said patent, wherein the nut may be released and the jaw slid to a desired position, it is necessary to more carefully position the nut by reverse rotation of the screw; otherwise it will reengage a second set of notches and prevent the nut from being moved rectilinearly with the screw. In the present invention a predetermined reverse movement of the screw releases the nut mechanism and, regardless of further reverse rotation, ears 38 merely abut flat surface 36 and slide therealong.

In Figure 3 the use of the beveled edges is shown wherein a face of work piece 44 is disposed on the 45° bevels 18, 19. The top edge 45 may then be cut to a 45° angle by horizontal movement of the cutting tools, this movement being the most natural for the workman.

Having described the invention, what we claim as new is:

1. A quick acting vise comprising an elongated body having a guide extending longitudinally on one side thereof, an apertured lug at one end of the guide, a vise jaw slideably connected with the guide, a screw extending through the aperture in the lug, one end of the screw being rotatably connected with the vise jaw, the screw being longitudinally slideable in the lug, abutment means on the screw comprising a plurality of juxtaposed members having upper and lower ears thereon, a plurality of longitudinally spaced transversely extending abutment members along the side of the guide facing the screw for the selective abutment of an end of an upper ear, the ears being of such thickness and spacing that only one of said ears may engage an abutment member on the guide in any particular position of said vise jaw on said body, and an uninterrupted surface on the guide below said abutment members against which a lower ear may engage and slide therealong.

2. A quick acting vise comprising an elongated body having a guide extending longitudinally on one side thereof, an apertured lug at one end of the guide, a vise jaw slideably connected with the guide, a screw extending through the aperture in the lug, one end of the screw being rotatably connected with the vise jaw, the screw being longitudinally slideable in the lug, abutment means comprising a pair of nuts threadedly engaging the screw having upper and lower ears thereon, a plurality of longitudinally spaced transversely extending abutment members along the side of the guide facing the screw for the selective abutment of an end of an upper ear, and

an uninterrupted surface on the guide below said abutment members against which a lower ear may engage and slide therealong.

3. A quick acting vise comprising an elongated body having a guide extending longitudinally on one side thereof, an apertured lug at one end of the guide, a vise jaw slideably connected with the guide, a screw extending through the aperture in the lug, one end of the screw being rotatably connected with the vise jaw, the screw being longitudinally slideable in the lug, abutment means comprising; at least one nut threadedly engaging the screw having upper and lower ears thereon, at least one plate member on the screw having upper and lower ears thereon, and means for retaining the plate member in spaced relation to the nut; a plurality of longitudinally spaced transversely extending abutment members along the side of the guide facing the screw for the selective abutment of an end of an upper ear, and an uninterrupted surface on the guide below said abutment members against which a lower ear may engage and slide therealong.

4. A quick acting vise comprising an elongated body having a guide extending longitudinally on one side thereof, an apertured lug at one end of the guide, a vise jaw slideably connected with the guide, a screw extending through the aperture in the lug, one end of the screw being rotatably connected with the vise jaw, the screw being lon-
